HARRY E. LA BOUR, OF CHICAGO HEIGHTS, ILLINOIS.

METHOD OF AND MEANS FOR INTIMATE MIXING OF FLUIDS.

1,318,774.

Specification of Letters Patent. Patented Oct. 14, 1919.

Application filed April 8, 1918. Serial No. 227,206.

To all whom it may concern:

Be it known that I, HARRY E. LA BOUR, a citizen of the United States, residing at Chicago Heights, in the county of Cook and State of Illinois, have invented a certain new and useful Improvement in Methods of and Means for Intimate Mixing of Fluids, of which the following is a full, clear, concise, and exact description, reference being had to the accompanying drawings, forming a part of this specification.

My invention relates to method of and means for intimate mixing of fluids.

While the invention is particularly applicable to the mixing of gases and liquids, I do not intend to limit the same to the above function, as it is applicable to the mixing of fluids in general. In devices of the prior art for the bringing together and mixing of gases and liquids, great difficulty has heretofore been experienced, first, in producing an efficient and uniform fluid curtain, second, in handling corrosive fluids or those containing sediment and third, in obtaining efficient mixing without breaking the fluid up into a fine spray or mist which must later be washed to prevent entrainment. The problem of mixing fluids, as for instance a liquid and gas, has heretofore been generally met by spraying or atomizing the liquid into a chamber of relatively stationary gas or into a current of gas, or by passing the gas through the body of liquid. The contact between the gas and the liquid is, at best, far from intimate and is relatively limited and not satisfactory. My invention has been designed to overcome the difficulties above enumerated. I have conceived the possibility of securing much greater efficiency and greater effect by embodying a number of novel actions or principles in a device for such mixing of fluids.

I have discovered that a liquid can be brought into intimate mixture with the gas for purposes of evaporation, chemical action or the like and then completely separated without entraining any appreciable amount of the liquid as such. I move the liquid in the form of an expanding sheet or curtain which breaks up into drops or droplets and I move the fluid in a similar expanding sheet or curtain at a small angle to the line of movement of the liquid sheet or curtain, so that the two sheets or curtains are brought into intimate contact for a rela-

tively long period of their travels. Preferably these sheets or curtains of liquid and of gas are produced by rotary apparatus, but it is to be understood that plain jets or nozzles of a suitable character may be employed. The casing about the two curtains is in the form of a downwardly flaring wall. This wall causes the liquid to be deflected downwardly into a dead space or pocket, or what might be termed a zone or region of quiet where the liquid may settle and be withdrawn. The gas passes upwardly and out of the top of the casing.

I have discovered that by giving the gas a rotary motion as it passes up along the converging walls, it throws down any drops or particles of liquid that might be entrained.

I have discovered further that the efficiency may be still further increased by giving the liquid a rotary motion, so that when the same breaks up into drops this motion will cause the drops or droplets to rotate individually. This I consider has a double effect; first, of causing continuous wiping action of the surface of the curtain and the individual droplets upon the surrounding gas and second a rotative motion of the particles develops a centrifugal effect which tends, even if small, to overcome to some extent the surface tension of the liquid. A further novel principle which I have embodied is that of expanding the gas to rarefy the same during the period that such intimate mixing occurs and then later subjecting it to compression, preferably by a centrifring action, particularly for throwing out such particles as might be in suspension and not vaporized.

Other novel principles and actions are employed as will be clear from the following specification.

In one form of my invention which I have constructed and tested I employ a rapidly rotating spreading disk upon which the liquid is projected and from which it is thrown by centrifugal action in the form of a sheet or curtain of liquid that expands in area and finally breaks into individual drops or particles. Immediately below the disk I place an impeller element for the gas, which impeller tends to throw the gas outwardly in a relatively thin sheet or curtain immediately below the spreading spray of the liquid. The result is a thin standing sheet of gas below a thin standing sheet of liquid. The liquid, as it is spread out

wardly, breaks at a short distance from the spreading disk into drops or droplets which fly out and striking the downwardly inclined wall of the casing. The gas expands as it leaves the impeller element and therefore provides a better condition for the absorption of vapor from the liquid. The liquid striking the casing drops down into the lower part of the casing into a dead space or pocket while the gas passes on up through a gas outlet of smaller size. The provision of this dead space or pocket is of great importance as it permits the liquid to be deflected wholly out of the path of the current of gas. In the gas outlet the gas is passed through a smaller space and is there compressed. At the same time the whirling of the gas, produced by the rotating impeller, centrifuges the gas, throwing out and separating any particles of the liquid that have become entrained.

In order to acquaint those skilled in the art with the manner of constructing and practising my invention I shall now describe one embodiment of the same in connection with the accompanying drawings which form a part of the present specification.

Figure 1 is a plan view of the device embodying my invention with the upper part 30 of the casing removed;

Fig. 2 is a vertical sectional view;

Fig. 3 is a diagram illustrating the manner in which the gas passes through the curtain of liquid; and

Fig. 4 is a diagram illustrating the motion of the individual particles of liquid.

The liquid to be handled is pumped or fed upon a revolving plate or disk 1, as by means of the pipe 2, being discharged upon the center of the plate 1. The disk 1 is mounted upon a spindle 3 which has bearings as shown at 4 and 5, which in turn are supported upon the stationary spindle 6. The stationary spindle is secured upon a bracket 7 mounted upon the lower half 8 of the casing. The spindle 6 is preferably secured by the taper 9 and the nut 10 in the bracket 7. A cup 11 for lubricating material communicates with the bore in the central spindle 6, which is shown in dotted lines at 12. The central bore 12 has side outlets as indicated in dotted lines in Fig. 2, to permit lubricating material to be discharged within the space between the hollow spindle 3 and the stationary spindle 6. The hollow live spindle 3 is provided at its lower end with a pulley 13, by which the same is driven. If desired, the spindle may be otherwise mounted and driven.

A series of impeller blades 14 are formed preferably integrally on the lower surface of the spreading disk 1. These impellers have a recess 15 cut in the central part of the same to provide a balancing effect on the fluid discharged therefrom upon the spindle

3. These impellers serve as a centrifugal pump for throwing the lowermost curtain of fluid.

The upper part 17 of the casing is preferably formed conical for a purpose later to be described, the parts 8 and 17 being secured together by flanges 18 and bolts or rivets 19. The lower part of the casing 8 is provided with a horizontal bottom portion 20. This bottom part or member 20 is provided with a plurality of outlets 21 for the discharge of liquid and is provided near the center with a plurality of inlets 22 for the admission of gas or other fluid. A frusto-conical wall 23 separates the inlet 80 openings from the outlets to provide two chambers—namely the central chamber 25 for the admission of gases or other fluids and the mixing chamber 26 in which the fluids are intimately mixed.

A circular flange 27 extends around the lower edge of the frusto-conical wall 23 to form a liquid seal between the chambers 25 and 26. The lower edge of the wall 23 is cut away at intervals as shown at 28 to permit the escape of any liquid which enters the interior of the chamber 25 and to form a liquid seal between the lower edge of the wall 23 and the bottom wall 20 of the main casing. The inlet openings 22 are surrounded by flanges 30 which prevent the liquid seal from escaping therethrough.

A flange 31 is formed about the central opening through which the live spindle 3 passes and the live spindle 3 is provided with a petticoat 32 to form a seal about said live spindle. It can thus be seen that the two chambers are at this point effectively closed off from each other. The bearings are isolated from either gas or liquid by the above arrangement.

At the upper end of the conical wall 23 I have provided the conical wall or flange 33 which has a central opening 34 for admitting fluid from the chamber 25 to the recess 15 in the impeller element.

The lower edge of each impeller blade is inclined downward toward the live spindle 3 and the conical flange 33 is formed to fit relatively closely to the lower edges of said impeller 14.

The upper portion of the casing section 17 is provided with an outlet 35 being formed preferably with a flange 36 for the attachment of a discharge pipe.

The operation of the device thus described is as follows:

The liquid is pumped or otherwise discharged through the pipe 2 upon the center of the revolving disk 1. This disk is revolved at a high speed. The liquid then travels from the center to the edge of the disk and the liquid takes on a constantly increasing velocity and spreads out uniformly over the plate. There is, however,

a certain amount of slip between the liquid and the plate. This causes the liquid film to partake not only of an outward velocity, but also of a rolling and rotary motion which puts the liquid into violent agitation so that as it spreads outwardly it breaks up into drops. These drops then have an outward and circular motion and also a planetary or rotary motion on their own individual axes. This action is illustrated diagrammatically in Fig. 4 in which the droplet 37 has the forward motion represented by the arrow 38 and also the rotative or rolling motion illustrated by the arrow 39.

15 It will be seen from this that a fluid curtain of considerable density can be formed, which will still permit the passage of gas between the rolling drops and at the same time force intimate contact between the liquid and the gas. I have illustrated this action diagrammatically in Fig. 3 in which the drops 40 move outward to the left and at the same time the gas illustrated by the arrows 41 moves up through the rolling drops 40.

The upper half of the casing 17 is made conical, or of such a shape as will deflect the flying drops downward so that they may collect in the lower half of the casing 30 8 and pass out through the discharge or outlet openings 21. The fluid is thrown from the disk 1 against the conical casing 17, thus completing the liquid curtain entirely across the mixing chamber 26. Due to the 35 shape of the casing, the liquid is deflected downward and passes on out. The annular space below the mixing plane and between the conical walls 17 and 23 forms a dead space or pocket 50 into which the liquid is 40 projected by striking the inclined walls 17. Here the liquid is deflected out of the current of gas so that even if the liquid be broken into the form of a fine spray it will not be entrained but will be separated out 45 of the mixture. The spent gases passing through the fluid curtain, have a rotating motion in the same direction as that of the plate and due to the centrifugal force, they are scrubbed against the conical walls above 50 the curtain, thus still further preventing entrainment. I have found that the whirling action of the gases extends upward and persists in the discharge pipe for quite a distance, in some cases as much as 8 ft. This 55 centrifugal action throws out any particles which have been entrained and thoroughly scrubs the gases against the walls of the casing and the discharge pipe.

The lower part of the casing is preferably 60 provided with mounting lugs or feet 43 and the upper part of the casing is preferably provided with a discharge pipe 42 for the spent gases.

The gases enter the openings 22 and pass 65 into the chamber 25, passing up through

the inlet 34 to the impeller pump, from whence they are discharged at a small angle to the line of discharge of the liquid from the spreading disk or plate 1. As the gases are thrown from the impeller 14 they expand to a certain degree and are thus in an ideal condition to permit as large a proportion as possible of the liquid to be vaporized due to the intimate mixture and the reduced pressure. After the gases pass 70 up the conical wall of the casing section 17, as previously explained, they are subjected to the centrifugal action which scrubs them against the walls of the casing and simultaneously throws out any entrained particles of liquid.

The advantages of this apparatus and method of operation are apparent, particularly in the case of the mixing of corrosive materials or materials containing sediment. 85 I have found that the device is highly efficient for washing and moistening air. A further important use of this device is in the evaporation of moisture from liquids below the normal boiling point, such as 90 concentrating acids or alkalis. I have found by tests that the economy of one operation of this device approximates a single effect vacuum evaporation.

In the drawings I have shown only a few 95 rows of drops being thrown off of the disk 1. It is to be understood that the action is not dependent upon the amount of liquid thrown off from the disk. In practice I discharge the liquid upon the spreading 100 disk 1 at a much higher rate than would be assumed from the drawing, and in fact I discharge the liquid upon this plate very rapidly and to the extent of forming quite a dense curtain of liquid.

105 There are numerous situations where it is desired to absorb chemical vapors or gases in liquids and for this function my invention finds a very great use.

As a means for cooling hot liquids or 110 gases the device is of great use. I find that it is possible to cool hot alkaline solutions very efficiently with practically zero entrainment.

I do not intend to be limited to the precise 115 details shown, nor to the exact manner of procedure indicated.

I claim:

1. The method of intimately mixing a fluid and a gas, which comprises projecting the liquid in a thin stream or curtain, simultaneously discharging a blast of gas in the same general direction in contact with the liquid, and then deflecting the liquid laterally in one direction into a dead 120 space or pocket to separate the same from the gas and moving the gas laterally in the opposite direction.

2. The method of intimately mixing a gas and a liquid, which comprises projecting a 130

sheet of liquid radially from a central point, projecting a sheet of gas below the liquid radially and at a slightly upward inclination with respect to the liquid, passing said gas through the liquid, separating said liquid and said gas and collecting the gas above and the liquid below the region of mixture.

3. The method of intimately mixing a liquid and a gas, which comprises projecting a drop of liquid in a substantially horizontal direction, causing the drop to rotate on its axis, projecting a blast of gas below the drop in a path inclined upwardly to the horizontal, then deflecting the drop out of the blast of gas into a dead space or pocket, and then subjecting the gas to a centrifugal action to separate out any entrained part of the liquid.
- 10 4. The method of intimately mixing a gas and a liquid, which comprises projecting a curtain of drops of liquid and projecting a sheet of gas in substantially the same direction, passing the gas through the curtain of liquid, deflecting the liquid laterally out of the moving gas into a pocket or dead space and then subjecting the gas to centrifugal action to disentrain any of the liquid.
- 15 5. The method of intimately mixing a liquid and a gas which comprises projecting the liquid in a sheet or curtain of drops substantially horizontally and simultaneously projecting a blast of gas in a sheet or curtain below the sheet or curtain of liquid substantially horizontally but slightly upwardly, passing the gas upwardly through the liquid and deflecting the liquid down out of the blast of gas into a dead space or pocket.
- 20 6. The method of intimately mixing a gas and a liquid, which comprises projecting a sheet of liquid radially from a central point, projecting a sheet of gas below the liquid radially and at a slightly upward inclination with respect to the liquid, passing said gas through the liquid, deflecting the liquid out of the moving gas into a dead space below the region of mixture, and collecting the gas above the region of mixture.
- 25 7. The method of intimately mixing a gas and a liquid, which comprises projecting a drop of liquid in a generally horizontal path and projecting a blast of gas in contact with the drop of liquid in the same general direction, causing the drop to rotate in contact with the blast of gas, deflecting the drop of liquid out of the blast of gas and passing the gas up above the drop.
- 30 8. The method of intimately mixing a gas and a liquid, which comprises projecting a series of drops of the liquid in a plane, then projecting a blast of gas in a plane slightly inclined to the plane of the liquid, then passing the gas through the liquid, causing the drop of liquid to rotate in con-

tact with the blast of gas and deflecting the drop down into a dead space out of the path of the gas.

9. The method of intimately mixing a liquid and a gas, which comprises projecting a drop of liquid in a substantially horizontal direction, causing the drop to rotate on its axis, projecting a blast of gas substantially horizontally in contact with the drop, but at a slight upward inclination to the path of the drop, and then deflecting the drop downwardly into a dead space or pocket and moving the gas upwardly.

10. The method of intimately mixing a liquid and a gas, which comprises projecting a drop of liquid in a substantially horizontal direction, causing the drop to rotate on its axis, projecting a blast of gas below the drop in a path inclined upward to the horizontal, then deflecting the drop down out of the blast of gas and then subjecting the gas to centrifugal action to separate out any entrained part of the liquid.

11. The method of causing an intimate mixture of liquids and gases which comprises putting a column of gas into longitudinal motion and while it is in motion producing therein a region of rarefied pressure in the form of a transverse plane, projecting a liquid in the form of drops transversely through the column of said gas and through said plane.

12. The method of causing an intimate mixture of gases and liquids which comprises putting a column of gas into motion longitudinally, reducing the pressure in said column in a region extending transversely thereof, and projecting through said region of low pressure, liquid in the form of drops and causing the drops to whirl on their axes.

13. The method of intimately mixing a gas and a liquid, which comprises projecting a curtain of liquid drops into a body of gas moving in substantially the same direction, at reduced pressure and causing the drops to whirl on their axes and deflecting the drops down into a dead space or pocket out of the path of the gas.

14. The method of intimately mixing a gas and a liquid, which comprises projecting a curtain of drops of liquid and projecting a sheet of gas in substantially the same direction, passing the gas through the curtain of liquid, deflecting the liquid laterally out of the moving gas and then subjecting the gas to centrifugal action to disentrain any of the liquid.

15. In combination, a casing having a conical wall, a rotatable spreading disk in said casing, adapted to project a liquid against said conical wall and means for projecting a blast of fluid radially from under the disk.

16. In combination, a casing having a

- conical wall with its smaller end upward, a discharge opening at the upper end for gas and having discharge outlets at the lower end for liquid, a rotatable shaft, a 5 rotatable spreading disk for spreading liquid and projecting the same against said conical wall and a fluid impeller for projecting a fluid in the same general direction as the liquid from said disk.
17. In combination, a casing having an outlet in its upper end for gases and an outlet in its lower end for liquids, a separating wall in said casing forming a gas chamber, means for introducing gas into said 10 chamber, an impeller pump for projecting a sheet of gas radially outward and a spreading disk above said impeller pump for projecting a sheet of liquid outward.
18. In combination, a rotating disk for 15 spreading a liquid by centrifugal action and an impeller for lighter fluids immediately below said spreading disk and means for driving said disk and said impeller.
19. In combination, a casing having a 20 conical wall with its smaller end upward, a discharge outlet at said smaller end, a rotatable spreading disk adapted to project a sheet or curtain of liquid against said conical wall, and means for forcing a blast 25 of lighter fluid radially outward and through the sheet or curtain of liquid.
20. In combination, a mixing chamber, a 30 gas chamber, a liquid inlet pipe, a spreading disk in the mixing chamber, an impeller pump below the spreading disk and in communication with the gas chamber 35 and means for rotating said spreading disk and said impeller pump.
21. In combination, a casing having a 40 lower portion and an upper conical portion with a gas outlet at the upper end of the conical portion, a circular wall within said casing and forming, in connection with the bottom of said casing, a gas chamber, means 45 for maintaining a liquid seal on said gas chamber, an inwardly extending flange on said latter conical wall, the gas impeller member fitting closely said flange, said impeller member communicating with the gas 50 chamber and a spreading disk for liquid above the impeller member.
22. In combination, a gas chamber having a circular wall with a flange, a spindle passing axially through said annular flange, 55 a rotating member on said spindle, said rotating member comprising a device for spreading liquid, and a plurality of impeller blades extending from below the device adjacent to the flange for drawing gas 60 from the gas chamber and projecting the same outwardly at a small angle to the angle of movement of liquid from the device.
23. In combination, a casing having a 65 conical wall with its smaller end upward, a discharge opening at the upper end, a spreading disk rotatably mounted in said casing for throwing a sheet or curtain of liquid against the conical walls, said liquid when projected against the conical walls being 70 adapted to be deflected downward, means for supplying liquid to said disk and means for projecting a blast of fluid through the sheet or curtain of liquid and at a small angle thereto.
24. In combination, a lower cylindrical casing having a closed bottom, a conical section joining the lower cylindrical section, said conical section having its smaller end upward and having a discharge opening in 80 the smaller end, an annular separating wall resting upon the bottom of the cylindrical casing section, a flange on the bottom wall for maintaining a liquid seal, an annular inturned flange on the upper end of said 85 annular wall, an impeller member moving close to said annular flange and a spreading disk above said impeller member.
25. In combination, a casing having a 90 mixing chamber and a fluid inlet chamber, a hollow live spindle projecting through one of said chambers, rotatable mixing means on said spindle and a stationary spindle rigidly mounted with respect to the casing and projecting into the hollow live spindle, a floor 95 having an opening through which the spindles project, and frictionless means sealing said opening against the escape of liquids.
26. In combination, a casing having an 100 outlet at its upper end, a dead space or pocket at its lower end and an upwardly and inwardly inclined wall joining the wall of the dead space or pocket and the wall of the outlet, means for projecting liquid in a 105 thin curtain or stream toward the inclined wall at such an angle as to cause deflection of the liquid down into the dead space or pocket, and means for discharging a blast of gas in the same general direction as the 110 liquid and at a slight upward inclination thereto, said gas passing through the liquid in intimate contact therewith and out of the outlets.
27. In a device of the kind described in 115 combination, a casing having a wall inclined inwardly and upwardly, said casing having a pocket below said inclined wall, a rotatable spreading disk in said casing adapted to project liquid against said inclined wall and thereby deflect the same into 120 said pocket and means for projecting a blast of fluid radially from under the disk into contact with the liquid.
28. In combination, a casing having an 125 outlet, a sloping wall immediately below the outlet, a rotating disk for spreading a liquid by centrifugal action and for throwing the said liquid radially against said sloping wall, and a rotary element having 130

means for projecting lighter fluids immediately below said spreading disk and means for driving said disk and element.

29. The improvement herein described, 5 which comprises bringing a gas and a liquid into contact by projecting a drop of liquid whirling on its own axis through a region of the gas of less than atmospheric pressure, and then separating the drop of liquid 10 from the gas.

30. The improvement herein described, which comprises bringing a gas and a liquid into contact by projecting a drop of the liquid whirling on its own axis through a 15 region of the gas moving in substantially the same direction, thereby entraining the liquid in the gas, and then disentraining the drop from the gas.

31. The improvement herein described, 20 which comprises projecting drops of a liquid rotating on their own axes into a stream of gas in substantially the direction of flow of the gas and at high speed, whereby the

liquid is entrained, then deflecting the drops of liquid into a dead space or pocket and 25 thereby causing the disentrainment of the liquid drops.

32. The improvement herein described which comprises projecting a curtain of liquid drops through a moving body of gas 30 maintained at less than atmospheric pressure, and causing the drops to whirl on their own axes, then separating the liquid drops from the gas.

33. The improvement herein described, 35 which comprises projecting a curtain of drops of liquid, whirling on their own axes into a body of gas moving in substantially the same direction, thereby entraining the liquid, then deflecting the liquid at substantially right angles into a region of quiet, 40 thereby disentraining the liquid drops.

In witness whereof I hereunto subscribe my name this 5th day of April, A. D. 1918.

HARRY E. LA BOUR.
